1

This invention relates to the manufacture of organic compounds, and is more particularly concerned with a process for producing butadiene, thiophene, and certain derivatives of thiophene from normal aliphatic hydrocarbons containing four carbon atoms.

Butadiene is a well known compound and, in general, is a synthetic product. It is a valuable hydrocarbon useful in numerous organic syntheses, and particularly important as an intermediate in the manufacture of synthetic rubber. The prior art on the conversion of hydrocarbons to butadiene is rather large and embraces a variety of reactions. In most instances, monoolefinic hydrocarbons are the preferred starting materials. However, in many cases, a two-step process is involved wherein a paraffinic hydrocarbon, such as butane, is dehydrogenated to a monoolefinic hydrocarbon, such as butene, in the first stage, and subsequently, the monoolefinic hydrocarbon is dehydrogenated to a diolefinic hydrocarbon, such as butadiene, in the second stage.

The use of typical dehydrogenation catalysts of the chromium oxide type, for example, necessitates a two-step process, since the conditions for the formation of a monoolefinic hydrocarbon from a paraffinic hydrocarbon are quite different from those required for the conversion of a monoolefinic hydrocarbon to the corresponding diolefinic hydrocarbon in the presence of this type of catalyst. Higher temperatures, greatly reduced pressures, and shorter contact times are optimum for the latter conversion.

The disadvantages of two-stage processes are obvious when it is considered that the monoolefinic hydrocarbon must be separated from the first stage for processing in the second stage. Conversions per pass usually are kept low in order to avoid secondary reactions such as cracking, with resultant carbon and light gas formation. The use of catalysts entails, of course, periodic regeneration which involves high initial and operating costs.

Some processes have been proposed, however, whereby butane is converted to butadiene in one

5 step. Thus, United States Patent No. 2,224,155 discloses a process for converting butane to butadiene in the presence of chlorine with fused molten metal chlorides as catalysts. British Patent No. 524,918 and French Patent No. 853,646, describe the conversion of butane to butadiene at temperatures of 500—700° C. in the presence of a catalyst comprising at least 50 per cent zinc oxide in admixture with other metal oxides or salts. 10 However, the relatively high cost of the catalysts involved in these processes due either to the nature of the catalyst itself or to the relatively large amounts employed, has rendered the utility of these processes somewhat questionable from the standpoint of commercial feasibility.

15 Thiophene likewise is a well known organic compound and occurs, ordinarily, in the benzene fraction of coal tar distillates. The amounts of thiophene, usually present in the crude benzene fraction, are of the order of about 0.5%. The close proximity of the boiling points of thiophene and benzene renders the complete separation and recovery of thiophene from the benzene fraction, by fractional distillation, a somewhat difficult operation. Consequently, commercial benzene normally contains traces of thiophene. 20 However, since thiophene is amenable to sulfonation much more readily than benzene, thiophene can be removed from benzene in the form of its 25 sulfonate, by repeated treatments with concentrated sulfuric acid. This, of course, is an expensive operation.

30 Thiophene has been synthesized in a number of ways. In accordance with the syntheses of the prior art, acetylene has constituted a preferred source of thiophene. Thus, it has been proposed to produce thiophene by reacting acetylene with pyrites, with hydrogen sulfide in the presence of catalytic material, with sulfur in the presence or 35 absence of catalytic material, and with carbon disulfide. Other syntheses proposed have involved the reaction of other hydrocarbons with sulfur or hydrogen sulfide in the presence of various catalytic materials. Thiophene has been 40 produced also from butyl mercaptan by dehydro- 45

genation and cyclization, by cyclization of organic compounds, by interchange of hetero-atoms in heterocyclic compounds, etc. It must be noted, however, that the yields of thiophene in all of these syntheses generally have been uniformly poor, in some cases, only traces of thiophene or derivatives thereof being produced.

The inherent chemical character of thiophene indicates a potentially wide use of this compound in industrial applications; however, the costly nature of the methods of separating and recovering thiophene from crude benzene and the small yields obtained in the proposed syntheses, referred to hereinbefore, have somewhat limited the use of this compound commercially, the only present outlets of any consequence being the drug and dye fields.

Various attempts have been made to provide cheap and commercially feasible processes for producing thiophene; but as noted hereinbefore, processes embodying the methods known to the prior art have suffered from two disadvantages, the first being the availability and consequently, the cost of the charging stocks, and the second being the magnitude of the yields of thiophene achieved. Thus, and as is well known to those familiar with the art, when the charge stock of a given process has been readily available and its cost, therefore, has been relatively low, the yields of thiophene have been small; on the other hand, when the yields have been high, the cost of the charge stock has been high.

In the search for readily available and cheap charge stocks to synthesize organic compounds generally, butane has been reacted with sulfur. This reaction was carried out to determine what compounds would be formed and not for the express purpose of synthesizing thiophene or butadiene. However, not more than a mere trace of thiophene and no butadiene were reported. [Baker and Reid, Jl. Am. Chem. Soc., vol. 51, page 1566 (1929).]

We have discovered that thiophene, certain thiophene derivatives and butadiene may be produced in substantial amounts, by reacting separately preheated normal aliphatic hydrocarbons, containing four carbon atoms per molecule, with separately preheated sulfur, at elevated temperatures.

Accordingly, it is an object of the present invention to provide a process for manufacturing organic compounds. Another object is to provide a cheap and readily available source of thiophene, butadiene and certain derivatives of thiophene. A further object is to provide a cheap process for producing thiophene, butadiene and certain derivatives of thiophene which is commercially feasible. A more specific object is to provide a process for obtaining high yields of thiophene and butadiene from normal aliphatic hydrocarbons containing four carbon atoms per molecule. A very important object is to afford a process capable of carrying out the above objects by reacting separately preheated normal aliphatic hydrocarbons containing four carbon atoms per molecule, with separately preheated sulfur, at elevated temperatures.

Other objects and advantages of the present invention will become apparent to those skilled in the art from the following description taken in conjunction with the following drawings, in which:

Figure 1 shows a curve representing graphically the relationship between the yield per pass of 70

thiophene and the proportion of sulfur in the charge;

Figure 2 shows a curve representing graphically the relationship between the sulfur through-put and the reaction temperature;

Figure 3 shows a curve representing graphically the relationship between the ultimate yield of thiophene in recycle operation, and the reaction temperature;

Figure 4 shows a curve representing graphically the relationship between the yield per pass of thiophene and the reaction temperature; and

Figure 5 is a diagrammatic illustration of a plant for practicing the process of our invention.

Broadly stated, our invention provides a process for manufacturing thiophene, thiophene derivatives, and butadiene, which comprises separately preheating sulfur and one or more normal aliphatic hydrocarbons selected from the group consisting of normal butane and normal butenes (butadienes may also be used in the charge when thiophene is the final product of the process), to temperatures such that combining the sulfur and hydrocarbon material will give a mixture having a temperature in excess of about 850° F., mixing the preheated sulfur and preheated hydrocarbon material, maintaining the temperature of the mixture at temperatures in excess of about 850° F. for a period of time sufficient to produce the desired products, and reducing the temperature of the mixture to less than about 850° F.

A feature of the process of the present invention is that with the exception of hydrogen sulfide and a tar, thiophene or butadiene are the 35 principal compounds obtained. Carbon disulfide is also formed, but only in small amounts. The hydrogen sulfide produced may be regenerated almost quantitatively back to sulfur for use in the process by an inexpensive treatment, such as incomplete combustion into water and sulfur. The tar is obtained in amounts which are about equal to those of thiophene. Certain useful products may be obtained from this tar, for example, mercapto-thiophenes and other heavier derivatives 45 of thiophene. The balance of the tar or tar residue, containing about 75% of sulfur, may be processed for the recovery of sulfur which can then be recycled to the process. Thus, the sulfur in the tar residue may be recovered by burning the 50 residue to produce sulfur dioxide. The sulfur dioxide can then be reacted with hydrogen sulfide to produce sulfur.

Another feature of the process of the present invention is that the materials in the charge, i. e., normal aliphatic hydrocarbons containing four carbon atoms per molecule and sulfur, are cheap and plentiful. Generally speaking, the aliphatic hydrocarbons suitable for the process are the normal aliphatic hydrocarbons represented by the molecular formulas C_4H_{10} , C_4H_8 and C_4H_6 , the latter being used when thiophene is the final product of the process. These aliphatic hydrocarbons may be derived from any suitable source, as is well known in the art, and may consist either of normal butane or normal butenes or mixtures of them, or even butadienes or mixtures of butadienes with normal butane and/or normal butenes when the process is operated to produce thiophene. It should be observed, however, that for economical operation of our process, when thiophene is the desired end-product, it is not preferred to use a hydrocarbon charge consisting predominantly of butadienes because of their tendency to polymerize under the conditions of the process. A conventional source of normal butane

and normal butenes is the gases obtained around petroleum refineries. These gases may furnish substantially all the desired aliphatic hydrocarbons, or it may be necessary or desirable to obtain additional supplies, as is well understood. It must be noted that normal butane, an unreactive constituent of by-product refinery gases and of natural gas, which is used largely for its fuel value only, may be processed, in accordance with our invention, to give thiophene, for example, a valuable product which heretofore has been unavailable to industry because of its high cost.

An important feature of our invention is that in our process the reaction is highly selective. High yields of thiophene or of butadiene are obtained, and they may be recovered from the reaction product in a highly pure state using conventional and readily available equipment.

A very important feature of the present invention is that it provides a cheap and efficient method of producing thiophene or butadiene. In our process, no catalysts are employed, thereby avoiding the disadvantages attendant on their use, such as regeneration and replacement problems, as well as the use of special reaction chambers. The process is substantially a one-step process. In operation, appreciable amounts of butenes (and butadienes, when the process is operated to produce thiophene) will be found in the effluent from the reaction zone. These may be recycled to the reaction zone for further conversion into butadiene or thiophene, thereby increasing the overall yield of the desired product. The equipment required is essentially only a pair of corrosion-resistant alloy preheaters, a corrosion-resistant alloy reactor coil and a corrosion-resistant recovery system. The separation of hydrogen sulfide presents few difficulties, since most of it can be removed by suitable pressure fractionation equipment and the last traces removed by caustic scrubbing or other conventional hydrogen sulfide removal processes.

While relatively large quantities of sulfur are employed, it is nevertheless one of the cheapest and most non-critical chemical reagents. We have found, in the operation of our process, and as shown in Figure 1 and in Examples 1, 2, 3 and 4, that the relative proportions of sulfur and hydrocarbon material in the charge may be varied over wide limits.

The data presented in Figures 1, 2, 3 and 4 were obtained by pumping normal butane through a hydrocarbon preheater at a rate of 31 grams per minute. The preheater coil consisted of 20 feet of 0.15-inch internal diameter, 18-8 stainless steel tubing, immersed in a lead bath kept at various temperatures. Molten sulfur was pumped at various rates through a preheater coil consisting of 20 feet of $\frac{1}{8}$ -inch iron pipe size, 27% chromium stainless steel tubing, immersed in a lead bath kept at various temperatures. The preheated reactants were then sent through a mixing nozzle and then through a reactor consisting of 12 feet of $\frac{1}{8}$ -inch iron pipe size, 27% chromium stainless steel tubing immersed in a lead bath kept at various temperatures. The pressure drop across the reactor was about 12 pounds per square inch gauge, and the reaction time was about 0.07 second. The reaction product was quenched with a water spray to arrest further reaction. The quenching operation resulted in a separation of the reaction mixture into essentially two fractions, one a relatively non-volatile tar and the other the more volatile constituents comprising light hydrocarbon gases, including butadiene, but-

enes and unreacted butane; and vaporized sulfur compounds, including carbon disulfide and thiophene. The latter fraction was sent through water-cooled heat exchangers to a tar trap, and thence to a glass wool filter where the entrained tar mist was filtered out. The filtered vapors were subsequently sent through a countercurrent caustic scrubber maintained at a temperature of about 176° F. for the removal of hydrogen sulfide. The remaining vaporous reaction product stream was sent through an efficient cooling system and finally to an ice trap for collecting the crude thiophene. The off-gases from the ice trap were metered and samples thereof subjected to Podbielniak distillation. In those runs where recycle was used (Figures 2 and 3), the off-gases were compressed and liquefied and after bleeding off the light gases, were recycled to the hydrocarbon preheater.

Within rather wide limits of sulfur concentration, the selective conversion to butadiene or thiophene is substantially the same, although the conversion per pass is directly proportional to the amount of sulfur. However, too much sulfur results in poor efficiency in sulfur utilization per pass and favors the complete sulfurization of hydrocarbon material to carbon disulfide. On the other hand, too low a proportion of sulfur lowers the conversion per pass and the ultimate yield by increasing the overall thermal degradation of hydrocarbon material. Generally speaking, best results are obtained using a weight ratio of sulfur to hydrocarbon material varying between about 0.5 and about 4.0, although when butenes (or butadienes, when the process is operated to produce thiophene) constitute the bulk of the hydrocarbon material in the charge, the lower limit of the weight ratio may be lower than 0.5.

EXAMPLE 1

Butene-1 was processed with 10.9% by weight of sulfur at 1100° F. (exit gas temperature) in a coil reactor made of 0.15-inch inside diameter stainless steel tubing (coil volume 50 ccs.). Butene-1 and liquid sulfur were pumped through separate preheating coils for preheating to a temperature of about 1200° F. before mixing. The preheated vapors were combined through a simple Y-connection entering the reactor coil. The pressure drop across the reactor was 6 lbs. per square inch, the average pressure being 3 pounds per square inch gauge.

The charge rates were 24 ccs. of liquid butene-1 and 0.9 ccs. of liquid sulfur, per minute, giving a calculated reaction time of 0.15 second.

The reaction mixture was quenched and the quenched gas, which contained 12.2% by volume of hydrogen sulfide, was scrubbed free of hydrogen sulfide and collected in a gasometer for analysis. The scrubbed gas was subsequently treated with maleic anhydride and showed a conversion of butene-1 to butadiene of 8.0% by weight

EXAMPLE 2

Butene-1 was processed as in Example 1 with 29% by weight of sulfur. The reaction gases contained 26.6% by volume of hydrogen sulfide and the yield of butadiene per pass on butene-1 charged was 18.1% by weight.

EXAMPLE 3

Butene-1 was processed as in Example 1 with 36.0% by weight of sulfur. The reaction gases contained 33.8% by volume of hydrogen sulfide and the yield of butadiene per pass on butene-1 charged was 20.7% by weight.

EXAMPLE 4

Butene-1 was processed as in Example 1 with 61.6% by weight of sulfur. The reaction gases contained 50.0% by volume of hydrogen sulfide and the yield of butadiene per pass was 27.1% by weight on the butene-1 charged.

The selectivity of the reaction involved in the process of the present invention depends primarily upon two variables, namely, the reaction temperature at which the normal aliphatic hydrocarbon or hydrocarbons containing four carbon atoms per molecule are contacted with sulfur, and the reaction time or the time during which contact between the reactants is maintained at the reaction temperature.

The limits of operating temperature are fixed by the kinetics of the desired reaction and the kinetics of possible side reactions. We have found that the reaction temperature may vary between about 850° F. and about 1400° F. However, when butane is the predominant hydrocarbon reactant in the charge, the reaction temperature varies, preferably, between about 1100° F. and about 1300° F., when butadiene is the desired end-product, and between about 1000° F. and about 1200° F., when thiophene is the desired end-product. When butenes (or butadienes when thiophene is the desired end-product) are the predominant hydrocarbon reactants in the charge, the reaction temperature varies, preferably, between about 900° F. and about 1300° F., when butadiene is the desired end-product, and between about 900° F. and about 1100° F., when thiophene is the desired end-product. Below the lower limit of the temperature range, as shown in Figures 2 and 3, when the process is carried out for the purpose of producing thiophene, for example, the reaction is so slow as to require a large through-put of sulfur and a higher ratio of hydrocarbon recycle for a fixed amount of end-product, therefore detracting from the economics of the operation. Further, the secondary reaction of tar formation consumes a larger proportion of the charge. Above the upper limit of the temperature range, as shown in Figures 3 and 4, when the process is operated to produce thiophene as the principal end-product, the secondary reaction of degradation of hydrocarbon material in the charge takes precedence, thereby decreasing the yield of desired product. In addition, to this, high temperatures favor the formation of carbon disulfide. It must be noted also, that at these high temperatures, corrosion problems are at a maximum, corrosion increasing perceptibly with increasing temperature.

As expected, we have found that the optimum reaction time depends upon the temperature employed. Generally speaking, other variables remaining constant, the lower the temperature, the longer the reaction time. The reaction or contact time and the reaction temperature are somewhat fixed, one in relation to the other, by the degree of degradation of the hydrocarbon material in the charge, and by the extent of formation of undesirable products, which may be tolerated. Thus, too long a contact time at high temperatures, results in severe cracking of the hydrocarbon material in the charge. The reaction proceeds with extreme speed, the only limitation apparently being the rapidity with which heat can be supplied to the reaction mixture. The reaction is highly endothermic, requiring, according to our experimental measurement, approximately 28,000 calories per gram molecular

weight of thiophene produced from normal butane. The lower limit of the range of reaction time is fixed, therefore, by the engineering problem of heat transfer and by mechanical limitations, such as allowable pressure drop across the reactor. Too long a reaction time at temperatures in the neighborhood of the lower limit of the temperature range, results in lower overall yields of thiophene or butadiene due to increased formation of heavy tar. On the other hand, too short a reaction time at temperatures in the neighborhood of the lower limit of the temperature range, results in insufficient reaction. Accordingly, we have found that for best results, the time of reaction is fixed by the reaction temperature.

The relationship between reaction temperature and reaction time is illustrated in the case where thiophene is the end-product, by the following tests:

TABLE I
Variation of reaction time with reaction temperature

No. of Test	Reaction Time in Seconds	Reaction Temperature in °F.	Weight Ratio of Sulfur to n-Butane in Charge	Yield per pass of Thiophene Based on N-Butane, in Per Cent by Weight
5.....	0.07	1300	1.0	18.4
6.....	1.23	1000	1.0	19.9
7.....	5.66	900	1.0	19.4

It should be noted that in these tests, as the reaction time increases and the temperature decreases, the yield per pass of thiophene is essentially constant. The calculated ultimate yield of thiophene remains also substantially constant being approximately 70% by weight based on the n-butane charged. Likewise, the degree of degradation of the reactants and the yields of by-products remain substantially constant. Test No. 7 required the use of a reaction coil $\frac{3}{8}$ -inch iron pipe size, and 52 feet in length. Accordingly, tests for determining the possibility of employing longer periods of reaction time were not carried out in view of the inconvenient lengths of alloy tubing which would be required for the reactor.

At high temperatures, butane is more susceptible to cracking than butenes. Particularly when the process is operated to produce butadiene as the end-product, and when normal butane is the hydrocarbon reactant, the temperature-time factor is more critical. Since, as stated hereinbefore, it is undesirable for butane to be degraded to lower hydrocarbons such as methane, ethylene, propylene, etc., a temperature-time factor must be chosen which will give the least cracking and still allow a substantial dehydrogenation of the normal butane to butadiene. Fortunately, the dehydrogenation reaction with sulfur is much faster than the cracking reaction. This is illustrated by Examples 8, 9 and 10. Consequently, by controlling the reaction time at a given temperature, the cracking reaction can be kept at a very low level without markedly affecting the reaction with sulfur. By practically eliminating cracking through the use of very short reaction times, at a given temperature, the amount of useful recycle stock is greatly increased and hence the selective conversion or the ultimate yield is increased.

EXAMPLE 8

n-Butane was processed with 147% by weight of sulfur at 1200° F. (exit gas temperature) in a coil reactor made of 0.15-inch inside diameter stainless-steel tubing (coil volume 50 cc.). Liquid butane (at 28° C.) and liquid sulfur (at 140° C.) were pumped through separate preheating coils for preheating to about 1200° F. before mixing. The preheated vapors were combined through a simple Y-connection entering the reactor coil.

The charge rates were 14.4 cc. of butane and 5.7 cc. of sulfur per minute. A partial vacuum was applied to the exit of the reactor coil to give an average pressure close to atmospheric. The reaction time was 0.10 second.

Quenching of the reaction mixture was accomplished by the stream of steam in the ejector which was used to produce the partial vacuum at the exit. The quenched gas was scrubbed free of hydrogen sulfide (about 60% by volume) and collected in a gasometer for analysis. The recovery of gaseous product (free of H₂S) was 86% by weight of butane charged.

The analysis of the scrubbed gas was as follows:

Per cent by volume	
Methane	7.5
Ethylene	7.6
Ethane	2.4
Propene	9.8
Propane	0.7
Butadiene	20.4
Butenes	15.7
Butane	32.6
Residue	3.3

The yield of butadiene per pass was 19.0% by weight of butane, and the calculated ultimate conversion (including butene recycle) was 42%.

EXAMPLE 9

n-Butane was processed with 77% by weight of sulfur at 1215° F. (exit gas temperature) in a stainless-steel baffled tube, constructed with the baffles extending out from the tube wall to provide heat conducting fins for better heat transfer to the rapidly flowing gas stream. The volume of this reactor was 30 cc. Liquid butane (at 22° C.) and liquid sulfur (at 150° C.) were pumped through separate preheating coils and the preheated vapors combined at 1200° F. through a mixing jet consisting of two 1/8-inch orifices opposing one another at a 180° angle.

The charge rates were 46.4 cc. of butane and 11.4 cc. of sulfur per minute. No vacuum was applied to the reactor exit since the pressure drop in this reactor was only 4 lbs. per square inch. The average pressure was 2 lbs. per square inch gauge and the reaction time was 0.026 second.

The recovery of H₂S-free gas was 91.6% by weight of butane charge. The analysis of this gas was as follows:

Per cent by volume	
Methane	0.0
C ₂ -hydrocarbons	2.6
C ₃ -hydrocarbons	2.9
Butadiene	13.8
Butenes	30.7
Butane	45.7
Residue	4.3

The yield of butadiene per pass was 12.0% by weight of butane, and the calculated ultimate conversion (including butene recycle) was 50%.

EXAMPLE 10

n-Butane was processed with 100% by weight of sulfur at 1210° F. in the same reactor described in Example 8. The pressure and reaction time were approximately the same as in the previous example.

The recovery of H₂S-free gas was 88.6% by weight of butane charge, and the analysis of this gas was as follows:

Per cent by volume	
Methane	0.0
C ₂ -hydrocarbons	3.5
C ₃ -hydrocarbons	3.3
15 Butadiene	17.1
Butenes	17.6
Butane	54.3
Residue	4.2

20 The yield of butadiene per pass was 14.5% by weight of butane, and the calculated ultimate conversion (including butene recycle) was 47%.

We have found, for example, that in the conversion of butane to butadiene, the best temperature-time relationship is defined by a reaction time of 0.03-0.08 second at about 1200° F. or somewhat higher. Other tests were made in which the reaction with normal butane for the conversion to butadiene was carried out at temperatures 30 of 1000-1100° F. Only a relatively small conversion to butadiene was noted (3-4% per pass). It would thus appear that, in so far as the conversion of normal butane to butadiene is concerned, the preferred lower temperature limit for 35 the process is around 1100° F. This is not, however, the case with butenes, since tests indicate that fairly satisfactory results can be obtained in the temperature range of 900-1100° F. However, even with butenes, better yields of butadiene 40 were obtained at temperatures of 1250° F., and much better conversion was obtained at the higher temperatures within the temperature range of our process as indicated hereinbefore.

In view of the foregoing, the criteria to be used 45 in determining optimum operating temperatures within the range 850°-1400° F., and reaction times are to choose the degree of conversion of product desired commensurate with operating costs such as heat input and equipment costs, 50 bearing in mind that within limits, the shorter the reaction time and concordantly, the higher the temperature, the larger the amount of desired end-product which can be realized from a unit of given size per day.

55 In general, the relationship between the temperature of reaction and reaction time is not singular with our invention. It is a well established and fairly well understood relationship in numerous reactions. In the present instance, we 60 have found that butadiene or thiophene, as well as certain derivatives of thiophene, may be produced by reacting separately preheated sulfur and normal aliphatic hydrocarbons containing four carbon atoms per molecule at a temperature falling 65 within the range varying between about 850° F. and about 1400° F., for a period of time selected to minimize the yields of secondary reaction products, i. e., carbon disulfide, hydrocarbons lower than C₄-hydrocarbons, and tar residue, at the 70 selected temperature. Accordingly, for the reaction temperature range of our process, i. e., 850° F. to 1400° F., when operating continuously with a reactor coil of suitable size and at a practical charge rate, we have found that the 75 lowest practical limit of the time of reaction is

of the order of 0.01 second at about 1400° F. The upper practical limit of reaction time, other variables remaining constant, will correspond to the lower limit of the temperature of reaction and may be of the order of several seconds. In view of the foregoing, it will be appreciated that the period of time to be used at a selected reaction temperature within the range indicated, can be readily determined by one skilled in the art.

Separate preheating of the hydrocarbon reactant and sulfur, and quenching of the reaction mixture are necessary for achieving the desired control of the reaction time at a given reaction temperature. Indeed, our process is operative, as will be explained hereinafter, due to this feature of separate preheating of the reactants. This is very important in the specific reaction producing butadiene or thiophene. Without any intention of limiting the scope of the present invention, it is suspected that a number of reactions occur in the reaction between the hydrocarbon reactant and sulfur. In this connection, the following reactions should be noted: Cracking of the hydrocarbon reactant destroying the four carbon-atom straight-chain structure (four carbon atoms in a straight chain being a prerequisite for the formation of butadiene or thiophene); dehydrogenation of the butane to the corresponding olefinic and diolefinc hydrocarbons; formation of tar high in sulfur; formation of carbon disulfide; and formation of thiophene. These reactions compete with one another. We have found that the rates of the cracking reaction and of the formation of carbon disulfide are somewhat slower than that required for the formation of butadiene or thiophene. Accordingly, a proper control of the reaction time at a given reaction temperature achieved by separate preheating, mixing, heating at a given temperature for a corresponding period of time, and quenching, is necessary to produce high yields of thiophene or butadiene with limited yields of carbon disulfide and fixed gases due to a limited decomposition of the hydrocarbon reactant. The rate of the reaction producing tar is fairly close to that required for the formation of butadiene and thiophene, and, therefore, the control of this reaction is more difficult. Hence, in spite of the separate preheating and ultimate quenching of the reaction mixture, the yields of tar approximate those of thiophene or butadiene.

In carrying out the process of the present invention, therefore, it is essential to separately preheat the reactants. Heating the hydrocarbon material and the sulfur together has two undesirable effects. In the first place, at lower temperatures, the reaction producing tar formation is the favored reaction; and in the second place, these heavy products are subsequently cracked in the reactor at the selected reaction temperature, causing undue coking. Tests have shown that when the reactants are heated together up to temperatures within the aforementioned reaction temperature range, excessive tar formation always results, and in such quantities, that the reaction zone becomes plugged with a heavy, carbonaceous deposit, in a very short period of time. Accordingly, it is essential in our process to separately preheat each of the reactants, i. e., the hydrocarbon or the mixture of hydrocarbons constituting the hydrocarbon reactant, and sulfur, to such temperatures that when they are brought together, under proper conditions of flow, a temperature falling within the reaction temperature range is achieved, before effecting con-

tact between them. In practice, this is effected ordinarily, by separately preheating each of the reactants to temperatures within the reaction temperature range.

After the separately preheated hydrocarbon reactant and sulfur are mixed and allowed to react for the reaction time indicated by the operating temperature, the temperature of the reaction mixture is immediately lowered to below about 850° F., in practice, appreciably below 850° F., for example, 300° F., in order to avoid over-reaction in the system after leaving the reactor. This may be achieved suitably by quenching the effluent of the reactor with a liquid.

As stated hereinbefore, in spite of the separate preheating and ultimate quenching of the reaction mixture, the yields of tar always approximate those of thiophene or butadiene. However, certain valuable products, more particularly, certain thiophene derivatives, as pointed out in pending applications, Serial Number 721,453, filed January 10, 1947, and Serial No. 721,454, filed January 10, 1947, can be recovered from the tar. These thiophene derivatives are useful as intermediates in organic synthesis. This tar is a black, mobile liquid which varies slightly in composition and physical properties, depending upon the reaction conditions used in the process. A typical sample had the following properties:

Specific gravity at 28/15.6° C. 1.5066
Pour point ..... Minus 15° F.
Viscosity, Saybolt at 210° F. .... 46 seconds
Heat and combustion ..... 9684 B. t. u./lb.

The tar was essentially miscible with a concentrated aqueous solution of potassium hydroxide indicating the presence of constituents of an acidic nature. A sample of the tar was subjected to vacuum distillation at 2 mm. absolute pressure and produced about a 50% distillate, about two-thirds of which upon redistillation boiled below 100° C. at 2 mm. absolute pressure. Indications are that vacuum distillation is a destructive distillation since no product is steam distillable from the original tar, whereas the vacuum distillates can be steam distilled readily. The fraction boiling below 100° C. at 2 mm. absolute pressure was tested to obtain the following data:

TABLE II

Property	Low-Boiling Vacuum Distillate	Theoretical Value for Mercapto-thiophene (Thiophene Thiol)
Boiling Point, °C. at 760 mm.	171	1 166
Molecular Weight	128	116
Saponification No.	438	483
Sulfur Content, Per Cent by weight	54.9	55.2
Carbon Content, Per Cent by weight	41.9	41.3
Sulfur as SH, Per Cent by weight (electrometric titration)	28.0	27.6
Sulfur Content of Mercury Salt, Per Cent by weight	29.6	29.7
Refractive Index n_d^{20}	1.6153	-----
Specific Gravity, 25/25° C.	1.251	-----
Solubility, Soluble in Aqueous KOH and Most Organic Solvents, such as Aromatic Hydrocarbons, Ether, Chloroform, etc.	-----	-----

¹ Value reported in literature.

Infrared spectrum analysis of this low-boiling vacuum distillate indicated the presence of the thiophene nucleus and SH group.

The fraction boiling (upon redistillation) at 115-135° C. at 2 mm. absolute pressure was again redistilled. A cut boiling at 121-123° C. at 2 mm.

absolute pressure was tested and the following data were obtained:

TABLE III

Property	Fraction Boiling at 121-123° C. at 2 mm.	Theoretical for (Thithio-succinic anhydride)
Molecular Weight.....	157	148
Carbon Content, percent by weight.....	34.46	32.4
Hydrogen Content, percent by weight.....	2.60	2.70

Electrometric Titration, N.N.....	-----	-----

¹ Difficultly soluble in aqueous KOH.

The material does not undergo mercaptan reaction such as the formation of mercury salts, mercaptide formation with 2,4-dinitro-chlorobenzene, etc., and will not undergo mercaptan analysis—electrometric method depending upon the precipitation of silver salt, indicating the absence of SH groups.

As stated hereinbefore, for economical operation of the process, when thiophene is the desired end-product, we prefer not to use a hydrocarbon charge consisting predominantly of butadiene because of its tendency to polymerize in the pre-heater with consequent cracking and severe coking in the reactor. However, when butadiene is used in conjunction with predominant amounts of butane and/or butenes, or suitable diluents which are inert with respect to sulfur and to other reaction products of the process, for example, nitrogen, carbon disulfide, carbon dioxide, etc., it can be processed satisfactorily to give high yields of thiophene. For effective operation of our process, when thiophene is the desired end-product, we have found that butadienes should constitute a minor proportion (ordinarily, less than about 50% by weight) of the hydrocarbon feed.

In our process, the reaction is effected, preferably, at atmospheric pressure or under sufficient pressure to cause the flow of the reactants through the reactor and auxiliary system, under the desired reaction conditions. Tests have shown that the yield per pass and ultimate yield of butadiene or thiophene decrease with increase in pressure. However, even at appreciable pressures, butadiene or thiophene are nevertheless produced in substantial amounts. Accordingly, there appears to be nothing critical about pressure as a reaction variable. We have found that best results are obtained when turbulent flow is maintained through the reactor, suitably, a conventional coil-type pipe reactor. With this type of reactor, the desired turbulent flow may be achieved with a pressure drop of about 1 to 20 pounds across the coil, depending upon the size of the pipe and the length of the coil. Turbulent flow promotes heat transfer and assures good mixing of the reacting vapors of sulfur and hydrocarbon material.

In this connection, it should be noted that in so far as the production of butadiene in accordance with the process of the present invention is concerned, it has been a rather unexpected result that good yields of butadiene are obtained without the use of diluents or without employing reduced pressures. This is extremely important when it is considered that all commercial processes for the production of butadiene use diluents

such as steam or other inert gases, or are carried out at greatly reduced pressures, of the order of one-quarter of an atmosphere or below, absolute. For example, the recently described 5 Houdry process [Oil and Gas Journal, 41, No. 15, page 30 (1942)] is carried out at a pressure of 5-10 inches of mercury, absolute. It is stated therein that the yield of butadiene per pass at atmospheric pressure is only about 2%, while at 10 four inches of mercury, the yield is about 12%. This appears to be characteristic of all previously described processes, and even the thermal conversion of naphthas and gas oils requires dilution of the reactants with 5-10 volumes of steam, or 15 other diluent, per volume of hydrocarbon vapor in order to obtain yields as high as 5-8 per cent of butadiene.

The advantages of working at atmospheric pressure or without diluents are obvious. Thus, 20 for a given capacity plant operating under the conditions of the prior art, our process can convert up to eight times the amount of butane per unit time. Moreover, heat requirements are very 25 substantially reduced by the elimination of diluents, and no special means are necessary to control the pressure as is the case in subatmospheric pressure installations.

Recycling of the unreacted portion of hydrocarbon material in the effluent stream has been 30 found to be a desirable scheme for increasing the ultimate yield of thiophene or butadiene. This has the same effect as lengthening the reaction time without the attendant and undesirable degradation of hydrocarbon material, referred to 35 hereinbefore. When butane is the hydrocarbon reactant and thiophene is the desired end-product, it is suspected that the reaction proceeds stepwise with the formation of the corresponding olefinic hydrocarbon, diolefinic hydrocarbon, and 40 finally, thiophene, each step causing the formation, simultaneously, of hydrogen sulfide, molecular weight for molecular weight. These reactions occur concurrently and unreacted butane as well as butenes and butadienes are found in the effluent. Indeed, whether the process is operated for 45 the production of butadiene or thiophene, butadiene and thiophene are always formed. Only traces of acetylenic hydrocarbons have been found. These hydrocarbons in the effluent (only 50 butane and butenes, when the process is operated to produce butadiene) serve as recycle stream in the recycling operation. In this connection, and when the process is operated to produce thiophene, it must be observed that when 55 butenes are the sole constituents of the hydrocarbon reactant, recycling of the hydrocarbons in the effluent is not commercially feasible in view of the high concentration of butadienes in the recycle stock. However, and as stated hereinbefore, butane or other suitable diluents may be 60 added to the recycle stock and the latter processed to give high yields of thiophene.

Accordingly, a most important feature of our process is that it is flexible, it being possible to 65 produce butenes as well as butadienes and thiophene from butane, or butadienes and thiophene from butenes, or thiophene from butadiene.

A plant for practicing the process of our invention is illustrated diagrammatically in Figure 5. 70 It is understood, of course, that certain modifications of this operating scheme, as well as changes in the type of equipment employed, may be made as long as the essential requirements of the process are maintained, as will be obvious to those skilled in the art, once the conditions of the proc-

ess, with which this invention is concerned, are clearly understood.

Referring now more particularly to Figure 5, which illustrates diagrammatically a plant for producing thiophene and/or butadiene, as well as certain thiophene derivatives, as stated hereinbefore, in accordance with our process, normal butane is pumped from a storage sphere 4 by a pump 5, to a preheater coil 6. Molten sulfur is pumped from a storage tank 1 by a pump 2, to a preheater coil 3. The preheated vapors of butane and sulfur are mixed at a point 7 prior to introduction into the reactor, and are then sent through a reactor coil 8. The preheaters 3 and 6 and the reactor 8 may each be in separate furnaces if desired, or, if in the same furnace, as shown, may be of different lengths to produce the desired preheating temperatures and reaction temperatures. As stated hereinbefore, for economical operation of the process of the present invention, short reaction times must be used. This requires rapid mixing of the reactants and rapid heat transfer to the reaction mixture. The reaction products enter a spray chamber 9 where they are quenched to a temperature of about 300° F., by spraying suitably with crude thiophene or some other liquid product of the process. The quenched reaction products subsequently are passed into a tar-separator 10, wherein tar separates out and is sent first to a vacuum still 20 where mercaptothiophenes and other thiophene derivatives are recovered, and then to a sulfur-recovery plant 19. The reaction products free of the bulk of the tar, go to a filter 11, to separate the tar mist. A Cottrell precipitator may be used as the mist collector if desired. The filtered products are then passed into a condensate stripper column 12 where most of the products that are normally liquid are stripped out. This column may be operated as an absorption stripper by using thiophene bottoms as the absorber liquid. The liquid bottoms from the condensate stripper column 12, go to a carbon disulfide tower 17 and the overhead to a compressor 13 and thence to a column 14 where C₃-hydrocarbon gases, gases lighter than C₃-hydrocarbons and hydrogen sulfide are removed as overhead and sent to the sulfur-recovery plant 19. The bottoms from the column 14, consisting of C₄-hydrocarbons and materials having boiling points higher than C₄-hydrocarbons, are passed into a column 15 where C₄-hydrocarbons are obtained as overhead and recirculated through a meter 16 to the preheater 6, and thus returned to the process as recycle stock. (Valve 22 is opened while valves 21 and 23 are closed.) The bottoms from the column 15 are combined with the bottoms from the condensate stripper column 12, and sent to the carbon disulfide tower 17. Carbon disulfide is taken off as overhead from the tower 17 and sent to storage, while the bottoms from the tower 17 are passed into a thiophene tower 18 where thiophene is taken as overhead and to storage and thiophene bottoms taken to storage to be used in the condensate stripper column 12 and/or as a quenching medium.

In a typical operation, the hydrocarbon material charged to the preheater coil 6 is made up of a normal butane cut containing varying amounts of butenes, obtained from a cracking unit for the conversion of gas oil into gasoline. Sulfur is charged to the preheater 3, in amounts to produce a mixture at 7 having a weight ratio of sulfur to butane cut, of about 1.0 and the charge rates are adjusted to give a reaction time

of about 0.05 second in the reactor coil 8 at a temperature to about 1200° F.

When the plant illustrated diagrammatically in Figure 5, is operated for producing butadiene, as well as thiophene and the thiophene derivatives, valves 21 and 23 are opened while valve 22 is closed. The overhead from the debutanizer 15 is passed into a butadiene absorber 24 where the C₄-hydrocarbons are contacted countercurrently with a selective butadiene absorbent, suitably, an ammoniacal cuprous chloride aqueous solution. The butane and butenes are obtained as overhead and are circulated through the meter 16 to the preheater 6, and thus returned to the process as recycle stock. The absorbent containing the butadiene is pumped by a pump 25 to a butadiene stripper column 26 where butadiene is removed from the absorbent with heat, butadiene comes off the stripper column 26 as overhead and is sent to storage. The hot absorbent free of butadiene is pumped by a pump 27 through a cooler 28 back to the butadiene absorber 24.

Detailed examples illustrating modes of producing butadiene in accordance with our invention have already been given hereinbefore.

The following detailed examples are for the purpose of illustrating modes of producing thiophene in accordance with our invention, it being clearly understood that the invention is not to be considered as limited to the specific manipulations and conditions set forth hereinafter.

EXAMPLE 1

A mixture containing 30% by volume of 1,3-butadiene and 70% by volume of normal butane was charged into a preheater at the rate of 35 grams per minute and heated to a temperature of 1100° F. Sulfur was charged to a separate preheater at a rate of 28 grams per minute and heated to a temperature of 1100° F. The two streams were sent through a mixing nozzle and thence through a baffled tube reactor of 50 c. c. volume constructed of 27% chromium stainless steel maintained at a temperature of 1300° F. The reaction product was quenched with a water spray, passed through a small Cottrell precipitator to remove tar mist, and scrubbed through a hot countercurrent caustic tower. Liquid product was condensed and separated in a water cooler and ice trap and the residual gas metered. 49% of the hydrocarbon material charged went to liquid product and tar. Fractionation of a portion of the stabilized (i. e., after removal of C₄-hydrocarbons and lighter constituents) liquid showed the following composition:

	Per cent
Carbon disulfide	9.0
Thiophene	80.5
Residue (mostly thiophene)	10.5

EXAMPLE 2

4959 grams of technical butene-2 (0.9% isobutylene, 98.5% butene-2 and 0.6% normal butane, by Podbielniak distillation), were charged at the rate of 49 grams per minute to a preheater coil consisting of 20 feet of 0.15 inch internal diameter, 18-8 stainless steel tubing, immersed in a lead bath, kept at 1190° F., and preheated to a temperature of 1160° F. 7230 grams of molten sulfur were charged at the rate of 71.7 grams per minute to a preheater coil consisting of 20 feet of $\frac{1}{4}$ -inch iron pipe size, 27% chromium stainless steel tubing, immersed in a lead bath kept at a temperature of 1320° F., and preheated to a temperature of 1290° F. The preheated reactants

were then sent through a mixing nozzle and then through a reactor consisting of 12 feet of $\frac{1}{4}$ -inch iron pipe size, 27% chromium stainless steel tubing immersed in a lead bath kept at a temperature of 1260° F., to give a temperature at the entrance to the quench tower, of 1250° F. The pressure drop across the reactor was 12 pounds per square inch gauge, and the reaction time was 0.03 second. The reaction product was quenched with a water spray, sent through water-cooled heat exchangers to a tar trap, and thence to a glass-wool filter where the tar mist was filtered out. The filtered gas was subsequently sent through a countercurrent caustic scrubber maintained at a temperature of 176° F. for the removal of hydrogen sulfide. The remaining reaction product stream was sent through an efficient cooling system and finally to an ice trap for collecting the crude thiophene. The off-gases from the ice trap were metered and subjected to Podbielniak distillation with the following results:

	Mole per cent	Grams
Hydrogen sulfide	0.4	3,892
Methane	3.4	3,340
C ₂ -hydrocarbons	2.7	1,610
C ₃ -hydrocarbons	6.3	3,020
Butenes	49.6	
Butadiene	35.2	
Butane	1.0	
Residue	1.4	

The following products were obtained:

	Mole per cent	Grams
Hydrogen sulfide	0.4	3,892
Liquid product	3.4	3,340
Off-gases	2.7	1,610
Tar	6.3	3,020

The liquid product was fractionated on a 15-plate column with the following results:

	Mole per cent	Grams
C ₄ -hydrocarbons	17.1	3,892
Carbon disulfide	8.9	3,340
Thiophene	71.5	1,610
Residue	2.5	3,020

EXAMPLE 3

The run described in Example 2 was repeated with the exception that 4870 grams of normal butane (containing 93 mole per cent normal butane and 6 mole per cent isobutane) were charged at a rate of 31 grams per minute, to the hydrocarbon preheater, simultaneously with 4370 grams of a recycle stream charged at a rate of 28.6 grams per minute. The recycle stream was obtained by compressing the off-gases obtained in the ice trap of Example 2; the compresses gases passing through a water-cooled heat-exchanger and thence, to a liquid hydrocarbon reservoir. The pressure in the hydrocarbon reservoir was maintained at 80 pounds per square inch gauge by bleeding off the proper amount of light gases resulting from thermal cracking. The recycle stream sent to the hydrocarbon preheater had the following composition:

	Mole per cent	Grams
Hydrogen sulfide	1.0	1.0
Methane	1.0	1.0
C ₂ -hydrocarbons	4.2	4.2
C ₃ -hydrocarbons	8.0	8.0
Butenes	14.2	14.2
Butadiene	23.3	23.3
Butane	47.2	47.2
Residue	1.0	1.0

In this run, 9860 grams of sulfur were charged to the sulfur preheater at a rate of 64.4 grams per minute. The pressure drop across the reactor was 8 pounds per square inch gauge, and the reaction time was 0.04 second.

The following results were obtained:

	Mole per cent	Grams
"Light" gases		1,073
10 Hydrogen sulfide	1.0	
Methane	36.6	
C ₂ -hydrocarbons	16.1	
C ₃ -hydrocarbons	5.0	
15 Butadiene	13.0	
Butenes	12.2	
Butane	15.6	
Residue	0.6	
Hydrogen sulfide		7,320
Tar		2,645
20 Ultimate analysis:		
	Per cent by weight	
Carbon	25.2	
Hydrogen	1.8	
Sulfur	73.0	
25 Crude thiophene		3,456
	Per cent by weight	
C ₄ -hydrocarbons	15.4	
Carbon disulfide	10.2	
Thiophene	72.4	
Bottoms	2.0	

This application is a continuation-in-part of co-pending application Serial Number 490,868, filed June 15, 1943, now abandoned.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

We claim:

1. The process for producing valuable organic compounds from normal C₄-hydrocarbons, which comprises separately preheating sulfur and a C₄-hydrocarbon selected from the group consisting of normal butane, normal butenes, and butadienes, to temperatures such that combining said sulfur and said hydrocarbon will give a reaction mixture having a temperature varying between 850° F. and about 1400° F.; mixing the preheated sulfur and the preheated hydrocarbon; reacting said preheated sulfur with said preheated hydrocarbon at a reaction temperature varying between about 850° F. and about 1400° F. to yield a mixture containing said organic compounds; and immediately reducing the temperature of the mixture containing said organic compounds to a temperature of less than 850° F.

2. The process for producing butadiene, which comprises separately preheating sulfur and normal butane, to temperatures such that combining said sulfur and said normal butane will give a reaction mixture having a temperature varying between about 850° F. and about 1400° F.; mixing the preheated sulfur and the preheated normal butane; reacting said preheated sulfur with said preheated normal butane at a reaction temperature varying between 850° F. and about 1400° F. for a period of time selected to minimize the yields of hydrocarbons containing less than four carbon atoms per molecule and carbon disulfide at said reaction temperature, to yield a butadiene-containing mixture; immediately reducing

the temperature of the butadiene-containing mixture to a temperature of less than 850° F.; and separating the butadiene from said butadiene-containing mixture.

3. The process for producing butadiene, which comprises separately preheating sulfur and normal butane, to temperatures such that combining said sulfur and said normal butane will give a reaction mixture having a temperature varying between about 1100° F. and about 1300° F.; mixing the preheated sulfur and the preheated normal butane; reacting said preheated sulfur with said preheated normal butane at a reaction temperature varying between about 1100° F. and about 1300° F. for a period of time selected to minimize the yields of hydrocarbons containing less than four carbon atoms per molecule and carbon disulfide at said reaction temperature, to yield a butadiene-containing mixture; immediately reducing the temperature of the butadiene-containing mixture to a temperature of less than about 850° F.; and separating the butadiene from said butadiene-containing mixture.

4. The process for producing butadiene, which comprises separately preheating sulfur and a normal butene, to temperatures such that combining said sulfur and said normal butene will give a reaction mixture having a temperature varying between about 850° F. and about 1400° F.; mixing the preheated sulfur and the preheated normal butene; reacting said preheated sulfur with said preheated normal butene at a reaction temperature varying between 850° F. and about 1400° F. for a period of time selected to minimize the yields of hydrocarbons containing less than four carbon atoms per molecule and carbon disulfide at said reaction temperature, to yield a butadiene-containing mixture; immediately reducing the temperature of the butadiene-containing mixture to a temperature of less than 850° F.; and separating the butadiene from said butadiene-containing mixture.

5. The process for producing butadiene, which comprises separately preheating sulfur and a normal butene, to temperatures such that combining said sulfur and said normal butene will give a reaction mixture having a temperature varying between about 900° F. and about 1300° F.; mixing the preheated sulfur and the preheated normal butene; reacting said preheated sulfur with said preheated normal butene at a reaction temperature varying between about 900° F. and about 1300° F. for a period of time selected to minimize the yields of hydrocarbons containing less than four carbon atoms per molecule and carbon disulfide at said reaction temperature, to yield a butadiene-containing mixture; immediately reducing the temperature of the butadiene-containing mixture to a temperature of less than about 850° F.; and separating the butadiene from said butadiene-containing mixture.

6. The process for producing thiophene, which comprises separately preheating sulfur and normal butane, the temperatures such that combining said sulfur and said normal butane will give a reaction mixture having a temperature varying between about 850° F. and about 1400° F.; mixing the preheated sulfur and the preheated normal butane; reacting said preheated sulfur with said preheated normal butane at a reaction temperature varying between 850° F. and about 1400° F. for a period of time selected to minimize the yields of hydrocarbons containing less than four carbon atoms per molecule

and carbon disulfide at said reaction temperature, to yield a thiophene-containing mixture; immediately reducing the temperature of the thiophene-containing mixture to a temperature of less than 850° F.; and separating the thiophene from said thiophene-containing mixture.

7. The process for producing thiophene, which comprises separately preheating sulfur and normal butane, to temperatures such that combining said sulfur and said normal butane will give a reaction mixture having a temperature varying between about 1000° F. and about 1200° F.; mixing the preheated sulfur and the preheated normal butane; reacting said preheated sulfur with said preheated normal butane at a reaction temperature varying between about 1000° F. and about 1200° F. for a period of time selected to minimize the yields of hydrocarbons containing less than four carbon atoms per molecule and carbon disulfide at said reaction temperature, to yield a thiophene-containing mixture; immediately reducing the temperature of the thiophene-containing mixture to a temperature of less than about 850° F.; and separating the thiophene from said thiophene-containing mixture.

8. The process for producing thiophene, which comprises separately preheating sulfur and a normal butene, to temperatures such that combining said sulfur and said normal butene will give a reaction mixture having a temperature varying between about 850° F. and about 1400° F.; mixing the preheated sulfur and the preheated normal butene; reacting said preheated sulfur with said preheated normal butene at a reaction temperature varying between 850° F. and about 1400° F. for a period of time selected to minimize the yields of hydrocarbons containing less than four carbon atoms per molecule and carbon disulfide at said reaction temperature, to yield a thiophene-containing mixture; immediately reducing the temperature of the thiophene-containing mixture to a temperature of less than 850° F.; and separating the thiophene from said thiophene-containing mixture.

45 9. The process for producing thiophene, which
comprises separately preheating sulfur and a
normal butene, to temperatures such that com-
bining said sulfur and said normal butene will
give a reaction mixture having a temperature
60 varying between about 900° F. and about 1100°
F.; mixing the preheated sulfur and the pre-
heated normal butene; reacting said preheated
sulfur with said preheated normal butene at a
reaction temperature varying between about 900°
55 F. and about 1100° F. for a period of time selected
to minimize the yields of hydrocarbons contain-
ing less than four carbon atoms per molecule
and carbon disulfide at said reaction tempera-
ture, to yield a thiophene-containing mixture;
60 immediately reducing the temperature of the
thiophene-containing mixture to a temperature
of less than about 850° F.; and separating the
thiophene from said thiophene-containing mix-
ture.

65 10. The process for producing thiophene, which
comprises separately preheating sulfur and a hy-
drocarbon feed comprising minor proportions of
a butadiene, to temperatures such that combin-
ing said sulfur and said hydrocarbon feed will
70 give a reaction mixture having a temperature
varying between about 850° F. and about 1400° F.;
mixing the preheated sulfur and the preheated
hydrocarbon feed; reacting said preheated sulfur
with said preheated hydrocarbon feed at a reac-
75 tion temperature varying between 850° F. and

about 1400° F. for a period of time selected to minimize the yields of hydrocarbons containing less than four carbon atoms per molecule and carbon disulfide at said reaction temperature, to yield a thiophene-containing mixture; immediately reducing the temperature of the thiophene-containing mixture to a temperature of less than 850° F.; and separating the thiophene from said thiophene-containing mixture.

11. The process for producing thiophene, which comprises separately preheating sulfur and a hydrocarbon feed comprising minor proportions of a butadiene, to temperatures such that combining said sulfur and said hydrocarbon feed will give a reaction mixture having a temperature varying between about 900° F. and about 1100° F.; mixing the preheated sulfur and the preheated hydrocarbon feed; reacting said preheated sulfur with said preheated hydrocarbon feed at a reaction temperature varying between about 900° F. and about 1100° F. for a period of time selected to minimize the yields of hydrocarbons containing less than four carbon atoms per molecule and carbon disulfide at said reaction temperature, to yield a thiophene-containing mixture; immediately reducing the temperature of the thiophene-containing mixture to a temperature of less than about 850° F.; and separating the thiophene from said thiophene-containing mixture.

12. The tar obtained by the process which comprises separately preheating sulfur and a C₄-hydrocarbon selected from the group consisting of normal butane, normal butenes, and butadienes, to temperatures such that combining said sulfur and said hydrocarbon will give a reaction mixture having a temperature varying between about 850° F. and about 1400° F.; mixing the preheated sulfur and the preheated hydrocarbon; reacting said preheated sulfur with said preheated hydrocarbon at a reaction temperature varying between 850° F. and about 1400° F. to yield a mixture containing said tar; immediately reducing the temperature of the mixture containing said tar to a temperature of less than 850° F.; and separating the tar from said mixture.

13. The tar obtained by the process which comprises separately preheating sulfur and normal butane, to temperatures such that combining said sulfur and said normal butane will give a reaction mixture having a temperature varying between about 1000° F. and about 1200° F.; mixing the preheated sulfur and the preheated normal butane; reacting said preheated sulfur with said preheated normal butane at a reaction temperature varying between about 1000° F. and about 1200° F. for a period of time selected to minimize the yields of hydrocarbons containing less than

four carbon atoms per molecule and carbon disulfide at said reaction temperature, to yield a mixture containing said tar; immediately reducing the temperature of the mixture containing said tar to a temperature of less than about 850° F.; and separating the tar from said mixture.

14. The tar obtained by the process which comprises separately preheating sulfur and a normal butene, to temperatures such that combining said sulfur and said normal butene will give a reaction mixture having a temperature varying between about 900° F. and about 1100° F.; mixing the preheated sulfur and the preheated normal butene; reacting said preheated sulfur with said preheated normal butene at a reaction temperature varying between about 900° F. and about 1100° F. for a period of time selected to minimize the yields of hydrocarbons containing less than four carbon atoms per molecule and carbon disulfide at said reaction temperature, to yield a mixture containing said tar; immediately reducing the temperature of the mixture containing said tar to a temperature of less than about 850° F.; and separating the tar from said mixture.
15. The tar obtained by the process which comprises separately preheating sulfur and a hydrocarbon feed comprising minor proportions of a butadiene, to temperatures such that combining said sulfur and said hydrocarbon feed will give a reaction mixture having a temperature varying between about 900° F. and about 1100° F.; mixing the preheated sulfur and the preheated hydrocarbon feed; reacting said preheated sulfur with said preheated hydrocarbon feed at a reaction temperature varying between about 900° F. and about 1100° F. for a period of time selected to minimize the yields of hydrocarbons containing less than four carbon atoms per molecule and carbon disulfide at said reaction temperature, to yield a mixture containing said tar; immediately reducing the temperature of the mixture containing said tar to a temperature of less than about 850° F.; and separating the tar from said mixture.

Certificate of Correction

Patent No. 2,450,659.

October 5, 1948.

ROWLAND C. HANSFORD ET AL.

It is hereby certified that errors appear in the printed specification of the above numbered patent requiring correction as follows:

Column 6, line 56, for "quenced" read *quenched*; column 12, line 34, for the words "Heat and combustion" read *Heat of combustion*; column 16, line 29, for "clearing" read *clearly*; column 17, line 58, for "presses" read *pressed*; column 19, line 5, claim 3, for "producting" read *producing*;

and that the said Letters Patent should be read with these corrections therein that the same may conform to the record of the case in the Patent Office.

Signed and sealed this 24th day of May, A. D. 1949.

[~~SEAL~~]

THOMAS F. MURPHY,
Assistant Commissioner of Patents.
